LIFT TRUCK WITH AUXILIARY TRUCK PICKUP

Alfred Erwin Reginald Arnot, Basingstoke, England, assignor to Emmanuel Kaye and John Reginald Sharp, both of Basingstoke, Hampshire, England

Filed May 16, 1957, Ser. No. 659,696

Claims priority, application Great Britain May 17, 1956

6 Claims. (Cl. 214—620)

This invention comprises improvements in or relating to goods-carrying trucks.

In U.S. patent application No. 553,354, now Patent No. 2,796,186, there is described a construction of lift truck comprising a mast and a vertically movable carriage thereon which is adapted to receive and to hold the back of an auxiliary truck having forks. The auxiliary truck can be detached from the carriage of the lift truck when desired, with its load upon it, and moved about independently.

In the aforesaid patent application, the carriage on the mast of the lift truck had a specially shaped front plate to centre and engage a hooked fixing on the auxiliary truck. Fork trucks however are standard equipment, of which there is normally a number in a works, and the necessity for such a specially shaped front plate prevents the use of the combination of fork lift truck and removable auxiliary truck except in cases where the standard fork lift truck has been specially modified. It is an object of this invention to provide a construction which can be used with any standard truck.

According to the present invention an attachment is provided which is capable of fitting the lifting carriage of a normal fork lift truck and constitutes an intermediate member having projections to enter apertures in the auxiliary truck, and the auxiliary truck is modified to receive said projections instead of hooking over the front plate of the lift truck carriage as heretofore.

It will be appreciated that the auxiliary truck has to be centralised with the lift truck when engaged and that this cannot be done exactly by manoeuvring the two trucks over the ground; hence the use of the specially shaped centering front plate on the prior truck. With the intermediate attachment used according to this invention the hooked fixing on the auxiliary truck, which was designed to co-operate with the specially shaped front plate as centering means, as well as lifting means, can no longer conveniently be employed and other centering means is needed.

To this end a pair of wide apertures is provided in the back of the auxiliary truck having centering faces at their upper ends and the projections on the intermediate attachment member enter the apertures in the back of the auxiliary truck and when lifted they engage the centering faces and centre the auxiliary truck relative to the lift truck.

Either or both trucks may be motor propelled if desired, but normally the masted lift truck would be motor propelled and the auxiliary truck would be a hand-truck. It is found moreover that with the known auxiliary trucks, when the masted lift truck approaches the auxiliary truck with a view to engaging it, the auxiliary truck tends to move away of its own accord and it is difficult to effect inter-engagement correctly.

According to the present invention, the auxiliary truck in addition to inter-engaging means is fitted with a brake which is capable of holding it during the engaging period and is preferably arranged so as to be automatically ap-

2

plied when the steering handle of the auxiliary truck is moved to a selected position in readiness for engagement.

The following is a description by way of example of one construction in accordance with the invention, reference being made to the accompanying drawings in which:

Figure 1 is a side elevation of part of a masted lift truck and of an auxiliary truck in accordance with the present invention, shown in the position into which they are brought prior to engagement;

10 Figure 2 is a rear view of the auxiliary truck;

Figure 3 is a plan of the same and of the intermediate attachment member;

Figure 4 is a front elevation of the attachment member;

Figure 5 is a side elevation of the same;

15 Figure 6 shows part of the internal mechanism of the auxiliary truck including the automatic brake;

Figure 7 is a section taken in plane at right angles to

Figure 6, of part of the automatic-brake mechanism;

Figure 8 is a plan of part of the auxiliary truck to a

20 larger scale than that shown in Figure 3; and

Figure 9 is a vertical section through one of the fork arms to show its internal mechanism.

Referring to Figure 1, the lift truck 11 is a standard

type of truck, comprising a chassis 12 having front wheels 13, a fixed mast 14, a rising mast 15 and a carriage on the rising mast having a flat vertical front plate 16 which is of standard form, and when not required for use according to the present invention carries the usual detachable fork members. According to the present invention there is an

30 intermediate attachment member 17 provided for the vertical plate 16 of the lifting carriage, which is shown in greater detail in Figures 3, 4 and 5. The attachment consists of two lateral plate members 18, 19 at the side which are united together by a lighter plate member 20 in the

35 centre. The front face of the member 20 lies in the same plane as the front faces of the side members 18, 19 and is welded thereto. The light central plate 20 is narrower in width at the top than the bottom and the side members 18, 19 are therefore inclined inwards toward the top.

40 At their rear upper edges they carry hook members 21, 22 which are notched at their undersides so as to hook over the top edge of the vertical plate 16 of the lifting carriage.

On the front face of the side members 18, 19 there are secured two forwardly and upwardly projecting inclined

45 bracket members 23, 24 which form hooks to engage apertures in the back of an auxiliary truck 25. The spacing of the two pick-up hook brackets 23, 24 is made to suit the size of the auxiliary truck 25 which is in use. The

50 lower ends of the side members 18, 19 of the intermediate attachment are wider apart than the upper portions thereof and they carry rearwardly projecting lugs 26 which, when the attachment is in place on the carriage plate 16, are capable of fitting just outside the side edges of the plate 16. These lugs are notched or drilled to permit

55 pegs 27 to be passed through them, one from each side

behind the plate 16 of the lifting truck and to thereby

hold the attachment securely in place.

The auxiliary truck 25 is in general similar to the corresponding truck described in the aforesaid U.S. patent application No. 553,354, but the rear upstanding portion

60 25 of the truck, which contains a steerable mounting 30 for a ground wheel 31, is made with a pair of apertures 32, 33 (Figure 2) which are large enough to receive readily the upwardly and forwardly projecting hooks or brackets 23, 24 on the intermediate attachment plate 18, 19, 20 already described. The apertures 32, 33 in the back of the auxiliary truck are made quite large and each has inclined shoulders or faces 34, 35 at its upper end which are inclined inwardly and upwardly as shown.

65 70 The result is that it is quite easy to manoeuvre the lift truck 11 into a position where the pick-up hook brackets 23, 24 can enter the apertures 32, 33, and when the lift-

carriage 16 on the mast 15 is raised the inclined upper faces 34, 35 centralise the auxiliary truck 25 relatively to the lift truck. To assist in this centralising action the upper edges of the pick-up hook members 23, 24 are themselves chamfered as shown at 36. The chamfers 36 extend in a sloping upwardly direction as viewed in side elevation, as can be seen from Figures 1 and 5, and this also assists in making the back of the auxiliary truck 25 slide down the members 23, 24 until the back of the auxiliary truck is firmly seated against the front face of the intermediate member 17.

The auxiliary truck 25 not only comprises the hollow back portion in which is the mounting for the steering wheel 31, but also forwardly projecting parallel fork members 37, 38, the front ends of which are supported on rollers 39 so that the truck can be wheeled about on the ground. A bail handle 40 is provided for pushing where heavy force has to be exerted, but there is also a steering tiller arm 41 having a handle 42 at its upper end for guiding and pushing the truck about under normal conditions.

Figure 6 shows the internal mechanism connected with tiller arm 41, which is located inside the upright rear portion of the truck 25, the mechanism being shown removed from the truck in Figure 6. It comprises a fixed cross-member 45 which is secured to the interior of the hollow upright portion of the truck 25 and which is provided with two hydraulic cylinders 46, 47, having rams 48, 49 connected to a cross-head 50. The hydraulic cylinders 46, 47 are single acting and they act to push downwardly on the cross-head 50 and so raise the truck. Springs 51 bring about the return movement. On the cross-head 50 are downwardly depending cam members 52, 53 which operate mechanism in the forks 37, 38 for raising the forks relatively to the rollers 39 as shown in Figure 9. The return movement for retracting the rollers 39 into the fork arms is assisted by springs 78 (Figure 9) located within the fork arms in addition to the action of the springs 51 in raising the cross-head 50. Also mounted on the cross-head in the centre is a ring 54 containing a ball-race 55 which supports a fork 56 in which is carried an axle 57 for the steering ground wheel 31. Extension of the jacks 46, 47 therefore raises the cross-member 45 relatively to the ground wheel 31 and at the same time causes the cams 52, 53 to raise the front ends of the forks relative to the rollers 39. The fork 56 which carries the ground wheel 31 is keyed to a steering column 58 and the upper end of the steering column is guided in a bush 59 in a bracket 60 on the transverse member 45. Therefore when the body of the truck is raised by the jacks 46, 47, the bush 59 slides up on the steering column 58. The upper end of the steering column forms the fork member 30 already referred to, in which is a pin 61 on which the tiller arm 41 is pivoted by means of a hub 62 mounted on the pin 41 between the side arms of the fork member 30. The hub 62 has in its centre a cam 63 which bears on a ball 64 carried on a tube 65 slidably within the steering column 58. The tube 65 rests on the spring 66 which in turn rests on a collar 67 secured to the inside of the steering column. Therefore the ball is urged upwardly against the underside of the cam 63. The tube 65 which supports the ball 64 is fixed to a brake rod 68 which extends down through the steering column to just above the wheel 31 through a bush 69 and carries at its lower end a brake-shoe 70. The cam 63 is so shaped that if the tiller arm 41 is moved upwardly past the vertical position into the position indicated by the chain-line 71 in Figure 7, the brake-shoe 70 will be firmly pressed down on the ground wheel 31. It will be noted that the cam edge has an indent to hold the tiller arm in the chain-line position. If the tiller arm is brought forward to the position of the lower chain-line 72, the brake is released and the truck can be pushed and steered by the handle 42. When the auxiliary truck is to be mounted

on the mast truck 11, it is wheeled into a position such as is shown in Figure 1, where its rear face is opposite to the upwardly inclined members 23, 24 on the intermediate attachment member 17, and the tiller arm is thrown upwardly to the chain line position 71 which puts the brake on the ground wheel 31. The mast lift truck is then moved forward to engage the members 23, 24 with the auxiliary truck and the carriage 16 is raised. This automatically seats the upright back portion of the auxiliary truck against the intermediate attachment member 17 and at the same time centres the auxiliary truck relative to the lift truck by the action of the inclined faces 34, 35 of the apertures 32, 33 upon the inclined faces of the members 23, 24. Further lifting movement of the carriage 16 raises the auxiliary truck off the ground to any height desired, the two trucks can be moved as one. The auxiliary truck can be deposited upon an elevated floor or platform or upon the ground, as desired, and disengaged and used for moving any goods which it carries to their ultimate position.

The plan view Figure 8 of the upright portion of the truck 25 shows how the handle 40 and the steering tiller arm 42 are disposed so as not to interfere with the operation of a pump handle 75. The pump handle 75 operates a pump 76 (shown in dotted lines) which draws hydraulic fluid through a reservoir 77 and delivers it to the jacks 46, 47 when the auxiliary truck is to be raised from the ground for running about.

A relief valve 80 permits the jacks to be retracted by springs 51 when desired. The relief valve 80 can also be opened after the auxiliary truck has been engaged and lifted by the masted truck. The action of springs 51 and the springs in the fork arms then retracts the ground wheel 31 and the rollers 39 and this permits the fork arms 37, 38 to be used like the fork arms of an ordinary masted lift truck whenever desired.

Figure 9 shows the internal mechanism for the fork arms 37, 38. The roller 39 of each fork arm is mounted on a lever 81 which is pivoted at 82 on a spindle which spans the space between the sides of the fork arm from side to side. The lever 81 is a double lever, having a single pivot and two arms which extend one at each side of the roller 39 and are slotted to engage the spindle 83 of the roller, which is held in the slots by screws passing through it.

The cam 53 has a vertical rear face 84 which is backed up by a bobbin-shaped roller 85 pivoted in the upright portion of the truck. The front face of the cam 53 engages a second bobbin-shaped roller 86 secured between the two sides of a double push rod 87 which extends forwardly within the box-shaped portion of the fork arm and is pivoted at its front end to the lever 81 by means of a pivot 88. This arrangement makes the lever 81 in effect into a bell crank lever. A pair of springs 78 draw the push rod 87 rearwardly when the cam 53 is raised relatively to the rollers 85, 86. In order to guide the rear end of the push rod 87 it is provided with side rollers 89 which run along the lower inner surface of the box-shaped fork arm. It will be appreciated that the fork arm is welded to the vertical part of the truck 25. The parts are shown in Figure 9 in the position in which a truck body is lifted relatively to the ground wheel 31 and the roller 39, but when the cam 53 is raised, if the truck is resting on the ground the fork arm 38, or 37, as the case may be, and the rear portion of the truck will descend to ground level. If the truck is mounted on the lifting carriage of a lift truck and the cam 53 is lifted by releasing the relief valve 80, the wheel 31 and the rollers 39 will rise into the body of the truck and into the fork arm respectively under the action of the springs. Auxiliary rollers 90, 91, 92, 93 and 94 are provided to guide the ends of the forks over the lower cross members or bottom deck of a pallet.

An alternative means of ensuring that the brake is "on" when the tiller handle is moved to the upright posi-

tion involves the employment of a Bowden cable for actuating the braking control. One end of the cable, between the castor wheel forks, is connected to a brake pad which is hinged to the forks and is urged into braking position by a strong spring. The cable, however, if tension is applied to it, is capable of pulling the brake pad off the wheel. The cable and its casing is led up the steering column and along the tiller handle to a brake release lever which extends alongside the hand-grip on the handle. If the hand-grip is grasped by the operator he will grasp the brake release handle at the same time and pull the brake off. When he lets go the brake is automatically put on by the spring, and the truck is ready to be engaged by the attachment on the lifting truck.

I claim:

1. In combination, a lift-truck comprising a wheeled body, a mast thereon, a lifting carriage on the mast adapted to support normally removable fork members, an intermediate carrier member adapted to fit said carriage in place of the normally removable fork members and having hook-like projections extending forwardly and upwardly from a position near the top of the carriage when the carrier member is in place therein, and an auxiliary fork truck having a wheeled body with an up-standing back portion and forwardly extending fork arms for engaging pallets, crates and the like, said back portion having apertures therein substantially wider than the said hook-like projections and adapted to fit on said hook-like projections, said apertures having inclined centering faces at their upper ends to engage the projections and center the auxiliary truck relatively to the fork lift truck.

2. Apparatus as claimed in claim 1 wherein the auxiliary truck, in addition to the inter-engaging means provided on it is fitted with a brake for the purpose described.

3. Apparatus as claimed in claim 1 wherein the auxiliary truck has means for moving the body thereof up and down relating to its wheels and means are provided to enable said wheels to be retracted when the auxiliary truck is attached to the carriage of the lift truck.

4. Apparatus as claimed in claim 2 wherein the steering handle of the auxiliary truck is operatively connected to the brake so as to be automatically applied when the steering handle is moved to a selected position.

5. Apparatus as claimed in claim 3 wherein the means for moving the body of the auxiliary truck up and down comprise a hydraulic jack device in the back portion of the body, a wheel mounting movable relatively to the back portion under the force exerted by said jack device, operative connections for said wheel mounting to rollers carried in the fork arms to move them when the wheel mounting is so moved, and a hydraulic pump device to operate the jack device.

6. Apparatus as claimed in claim 5 wherein the hydraulic jack is single acting and acts to extend the wheel mounting, retraction is effected by spring return means and the pump is provided with a relief valve to allow said spring return to act.
